LOUIS A. HAZELTINE, OF HOBOKEN, NEW JERSEY, ASSIGNOR TO HAZELTINE CORPORATION, A CORPORATION OF DELAWARE.

WAVE SIGNALING SYSTEM.

Original application filed February 27, 1925, Serial No 12,000, Patent No. 1,648,808, and in Canada May 4, 1925. Divided and this application filed October 31, 1927. Serial No. 229,912.

This invention relates to wave signaling systems, particularly radio receiving systems employing tuned radio-frequency amplification, and has for its object the provision of 5 means for securing substantially complete neutralization of the capacity coupling in vacuum tubes under certain circumstances.

In my United States Letters Patent No. 1,533,858, granted April 14, 1925, there are 10 described means for eliminating coupling between stages of an amplifier including the neutralization of the capacity coupling between the grid and plate electrodes of a vacuum tube and between the apparatus connected thereto. Such neutralization is 15 accomplished, briefly, by the use of an auxiliary coil and a neutralizing condenser connected in series between the grid and the filament system, the neutralizing coil being coupled 20 to a primary coil connected between the plate and the filament system.

In general for complete neutralization the coupling between the auxiliary coil and the primary coil should be so close as to behave 25 practically like perfect coupling—that is, with a coupling coefficient equal to unity. Now circumstances sometimes arise in which the coupling by choice or necessity is looser, no longer behaving like perfect coupling and 30 so resulting in incomplete neutralization. For example, at relatively low frequencies it may be desired to employ coils having their turns bunched or wound in "spiderweb" form or mounted on individual supporting structures, resulting in each case in a physical 35 separation of the coils. Again, at very high frequencies the reactances of the leads become appreciable even when the leads are made as short as feasible, thus also loosening the coupling between the circuits of the coils. In 40 accordance with this invention it has been found that substantially complete neutralization may be attained at all frequencies within the range of the amplifier provided that a 45 certain relation is maintained between the coupling coefficients of the auxiliary coil, the primary coil and the tuned secondary coil.

Referring to the drawings:

Fig. 1 shows the diagram of connections of 50 a radio receiver which includes a multistage radio-frequency amplifier having an arrangement of coils to which this invention has been applied.

Fig. 2 shows the structure of a radio-

frequency amplifying transformer the coils 55 of which are arranged in accordance with this invention and suited for use in a low radio-frequency amplifier such as represented in Fig. 1.

The receiver of Fig. 1, which is only a 60 single example of the many possible uses of this invention, is intended to operate a relay whose rate of operation corresponds to the pulses of a radio telegraph system. The radio pulses received by the antenna are amplified at radio frequency by the vacuum tubes A_1 and A_2 , with their tuned transformer circuits, are changed to low frequency by the detector tube D , are then amplified at the pulse frequency by A_1 and A_2 again, on the 65 reflex principle, and are finally amplified and supplied to the relay by the vacuum tube A_r . These and other details are more fully described in my copending application for United States Letters Patent No. 12,000, filed 70 February 27, 1925, issued November 8, 1927, as Patent No. 1,648,808, of which this present application is a division.

Interstage radio-frequency couplings are 75 minimized by the use of individual metal 80 compartments for each stage and by the use of series resistances R_p , R_g , or impedance L_{pd} , and shunt capacities C_p , C_g , C_{pd} , C'_{pd} and C_a , in the leads, and especially by the neutralization means involving coils L_{n1} , L_{p1} , L_{s1} , and 85 condenser C_{n1} in one stage, and coils L_{n2} , L_{p2} , L_{s2} , and condenser C_{n2} in the other stage.

The use for which the receiver of Fig. 1 is intended involves relatively low radio frequencies, where the single-layer type of secondary 90 winding (commonly used in broadcast receivers) is preferably replaced by a multilayer coil L_s and where the primary coil L_p and auxiliary coil L_n may be of the pancake form, placed close together, as represented in Fig. 95 2, where L_n , L_p , L_s indicate either L_{n1} , L_{p1} , L_{s1} , or L_{n2} , L_{p2} , L_{s2} of Fig. 1. With this arrangement, as previously mentioned, it is difficult to secure the exceedingly close coupling between L_n and L_p which is desired. 100 It has been found, however, that if the coupling coefficient between L_n and the secondary coil L_s is equal to the product of the coupling coefficient between L_n and L_p , and the coupling coefficient between L_p and L_s , then 105 the coefficient of coupling between L_n and L_p need not be substantially unity. This result may be attained with L_p placed between L_n and

L_s , as shown in Fig. 2. It is always best, however, to make the coupling between L_n and L_p as close to unity as feasible, for the nearer it approaches unity the easier it will be to attain the relation between the coupling coefficients just given.

The theory underlying the above-stated relation between coupling coefficients is as follows: The ordinary method of determining the proper value of neutralizing capacity, C_{n1} or C_{n2} , as described in my mentioned pending application, is to turn out the filament of the respective vacuum tube A_1 or A_2 being neutralized (allowing the filaments of the other vacuum tubes to remain lighted), to tune in a strong signal, and then to adjust the neutralizing capacity until the signal disappears. With close coupling between L_n and L_p , the relation then existing would be

$$\frac{C_{gp}}{C_n} = \frac{N_n}{N_p}, \quad (1)$$

where C_{gp} is the grid-plate coupling capacity, C_n is the neutralizing capacity and N_n and N_p are the numbers of turns of coils L_n and L_p , respectively, all for the stage being neutralized. If the coupling is not very close, the above procedure will result in the existence of the following more general relation,

$$\frac{C_{gp}}{C_n} = \frac{L_{ns}}{L_{ps}}, \quad (2)$$

where L_{ns} is the mutual inductance between L_n and L_s , and L_{ps} is the mutual inductance between L_p and L_s . Relation (2), of course, reduces to relation (1) for very close coupling, from the formula for mutual inductance, which for L_{ns} and L_{ps} would have identical factors except N_n and N_p , respectively.

Now when the filament is lighted, there will flow, in addition to the currents previously present, the amplified plate current. This current flows through coil L_p and gives rise to a self-induced voltage in that coil proportional to the self-inductance L_p , and to a voltage in coil L_n proportional to the mutual inductance L_{np} between L_n and L_p . If a balance is still to be maintained, it is necessary that these voltages produce equal (and, of course, opposite) additional currents through C_{gp} and C_n . Since the currents are proportional to the capacities, the latter must be inversely proportional to the respective voltages. Hence

$$\frac{C_{gp}}{C_n} = \frac{L_{np}}{L_p}, \quad (3)$$

Combining this relation with (2),

$$\frac{L_{ns}}{L_{ps}} = \frac{L_{np}}{L_p}. \quad (4)$$

Now the coefficient of coupling k between two coils is defined as the quotient of the mutual

inductance by the square root of the product of the self-inductances. Substituting this relation for each mutual inductance in (4) we have

$$\frac{k_{ns}\sqrt{L_n L_s}}{k_{ps}\sqrt{L_p L_s}} = \frac{k_{np}\sqrt{L_n L_p}}{L_p}, \quad (5)$$

which at once reduces to the relation stated above,

$$k_{ns} = k_{np} k_{ps}. \quad (6)$$

In practice it may not be necessary to have such precise neutralization as exactly satisfies equation (6). Merely placing L_p between L_n and L_s may suffice, for this at least makes k_{ns} less than k_{np} and k_{ps} , as it should be, since all k 's are less than unity. In particular, if L_n and L_p are close together, k_{np} will be near unity and k_{ns} will be only slightly less than k_{ps} ; this gives of itself a close approach to the condition (6), showing the advantage mentioned above of making the coupling between L_n and L_p as close to unity as feasible.

The above derivation does not consider the voltages induced in the leakage self-inductances of L_n and L_p , due to the capacity currents flowing through them. However, the consideration of capacity current in L_p leads to exactly the same result as above, since the derivation will apply to any current in L_p . The only error in neutralization that remains is thus that due to the capacity current in the leakage reactance of L_n , this error manifesting itself by a slight theoretical unbalance at frequencies differing from that at which C_n is adjusted. Since the capacity associated with L_n , consisting of natural capacity plus C_n , is ordinarily very small, and the leakage self-inductance is kept as small as feasible by fairly close coupling, this error can be shown to be ordinarily quite insignificant. The relations (2) and (6) therefore give substantially complete neutralization under all practical conditions.

A suitable experimental procedure for attaining the two relations required for complete neutralization is as follows: The filament of the vacuum tube to be neutralized is turned out and a strong signal is impressed between its grid and filament. The neutralizing capacity C_n and the coil couplings are then adjusted until no signal voltage appears between the plate and the filament, both when the output circuit is tuned and when it is not. The absence of signal voltage can conveniently be ascertained by a zero reading on a vacuuming tube voltmeter connected between the plate and filament system of the vacuum tube being neutralized.

This invention is applicable to any amplifier in which the secondary coil is connected in a closed alternating-current circuit, whether tuned or not. If the circuit is not tuned, the procedure described in the preceding paragraph is modified simply by obtaining a bal-

ance with at least two different impedance conditions in the secondary circuit, as for example, open circuit and short circuit.

I claim:

5. 1. In an electric circuit arrangement for neutralizing capacity coupling between the grid and plate circuits of a vacuum tube, including a primary coil connected between the plate and the filament system, a secondary coil, and an auxiliary coil and a neutralizing capacity connected in series between the grid and the filament system, the auxiliary and primary coils being utilized under such circumstances that substantially unity coefficient 10 of coupling between their circuits is not present, the method of securing substantially complete neutralization, which comprises arranging said coils so that the ratio of the mutual inductance between the secondary coil 15 and the auxiliary coil to the mutual inductance between the secondary coil and the primary coil is equal to the ratio of the mutual inductance between the auxiliary coil and the primary coil to the self-inductance of the primary coil and so that said ratios are also equal 20 to the ratio of the coupling capacity to the neutralizing capacity.

2. In an electric circuit arrangement for neutralizing capacity coupling between the grid and plate circuits of a vacuum tube, including a primary coil connected between the plate and the filament system, a secondary coil, and an auxiliary coil and a neutralizing capacity connected in series between the grid 30 and the filament system, the auxiliary and primary coils being utilized under such circumstances that substantially unity coefficient 35 of coupling between their circuits is not present, the method of securing substantially complete neutralization, irrespective of the currents flowing through the primary and secondary coils, which includes the step of interposing the primary coil physically between 40 the other two coils in such manner that the co-

efficient of coupling between said other two 45 coils is substantially equal to the product of the coefficients of coupling between the primary coil and each of the other coils.

3. In an electric circuit arrangement for neutralizing capacity coupling between the grid and plate circuits of a vacuum tube, including a primary coil connected between the plate and the filament system, a secondary coil, and an auxiliary coil and a neutralizing capacity connected in series between the grid 50 and the filament system, the auxiliary and primary coils being utilized under such circumstances that substantially unity coefficient 55 of coupling between their circuits is not present, the method of securing approximately 60 complete neutralization, irrespective of the currents flowing through the primary and secondary coils, which includes the step of interposing the primary coil physically between the other two coils in such manner that the coefficient 65 of coupling between said other two coils is less than the coefficient of coupling between the primary and either of the other coils.

4. In an electric circuit arrangement for 70 neutralizing capacity coupling between the grid and plate circuits of a vacuum tube, having a grid, a plate, and a filament system, the combination of a secondary coil, an auxiliary coil, and a primary coil physically interposed 75 between said secondary and auxiliary coils, whereby the coefficient of coupling between said secondary and auxiliary coils is less than the coefficient of coupling between said primary and either of the other coils said primary coil being connected between the plate and the filament system, said auxiliary coil being connected in series with a neutralizing capacity between the grid and said filament system, and said secondary coil being connected 80 in a closed alternating-current circuit.

In testimony whereof I affix my signature.
LOUIS A. HAZELTINE.
